(57) CLAIM

The ornamental design for a convertible golf bag, as shown and described.

DESCRIPTION

FIG. 1 is a top right side perspective view of a convertible golf bag showing a new design with a saddle bag attached to the golf bag;

FIG. 2 is a front side elevation view of the convertible golf bag as shown in FIG. 1;

FIG. 3 is a rear side elevation view of the convertible golf bag as shown in FIG. 1;

FIG. 4 is a left side elevation view of the convertible golf bag as shown in FIG. 1;

FIG. 5 is a right side elevation view of the convertible golf bag as shown in FIG. 1;

FIG. 6 is a top left perspective view of the convertible golf bag with a shoulder strap attached to the golf bag as shown in FIG. 1;

FIG. 7 is a top plan view of the convertible golf bag as shown in FIG. 1;

FIG. 8 is a bottom plan view of the convertible golf bag as shown in FIG. 1;

FIG. 9 is a top right perspective view of a convertible golf bag showing a new design without the saddle bag attached as shown in FIG. 1;

FIG. 10 is a front side elevation view of the convertible golf bag as shown in FIG. 9;

FIG. 11 is a rear side elevation view of the convertible golf bag as shown in FIG. 9;

FIG. 12 is a left side elevation view of the convertible golf bag as shown in FIG. 9;

FIG. 13 is a right side elevation view of the convertible golf bag as shown in FIG. 9;

FIG. 14 is a top right perspective view of a convertible golf bag without the saddle bag attached as shown in FIG. 9;

FIG. 15 is a top plan view of the convertible golf bag as shown in FIG. 9; and,

FIG. 16 is a bottom plan view of the convertible golf bag as shown in FIG. 9.

In the drawings, the shorter dash broken lines with shorter spacing are for the purpose of illustrating certain stitching that do not form part of the claimed design. In the drawings, the longer dash broken lines depict portions of the detachable saddle bag that form no part of the claimed design.
